UNITED STATES PATENT OFFICE.

WILLIAM B. SHEARER, OF NEW YORK, N. Y., ASSIGNOR TO INTERNATIONAL TORPEDO BOAT CORPORATION, OF WILMINGTON, DELAWARE.

TORPEDO-BOAT.

1,357,527.

Specification of Letters Patent. Patented Nov. 2, 1920.

Application filed January 29, 1919. Serial No. 273,851.

To all whom it may concern:

Be it known that I, WILLIAM B. SHEARER, a citizen of the United States, residing in the city, county, and State of New York, 5 have invented certain new and useful Improvements in Torpedo-Boats, of which the following is a specification.

In a previous application No. 206,407 I have described a torpedo boat the forepart 10 of which is a torpedo receiving space adapted to be flooded with water through which the torpedo is launched or propelled under its own power and the rear part of which is a closed space, separated by a 15 bulkhead from the forepart, just sufficient to carry the operating mechanism and the operator and to maintain the proper balance and flotation level. My present invention aims to provide an improvement whereby 20 such a boat can be loaded with a torpedo in a tube of the ordinary sort and from which it can be launched by the usual mechanism.

The accompanying drawings illustrate an 25 embodiment of the invention.

Figure 1 is a longitudinal section;

Fig. 2 is a plan, partly broken away;

Fig. 3 is a cross-section on the line 3—3 of Fig. 1;

30 Fig. 4 is a cross-section of a modification;

Fig. 5 is a plan of the same, opened to receive a torpedo.

Referring to the drawings, the boat comprises a rear closed space A or cock pit in 35 which the operator stands and which carries an engine B and the usual mechanism for driving and directing the boat, all of which are of the usual or any suitable type and need not be illustrated in detail. The 40 forward part C of the boat is of just sufficient length to accommodate a torpedo in its tube with the usual accessories. Its hull comprises bottom plates D (Fig. 3) and side plates E and a deck F (Figs. 1, 2 and 45 3) which is adapted to be moved or lifted sufficiently for the introduction of the torpedo. The deck of the cock pit may be of any suitable design, projecting slightly above the forward deck so that when the 50 boat is running approximately awash or slightly submerged the operator can see to direct his course. The bow G is formed as a removable section in front of the torpedo, with a hinge H at its upper end and 55 connected by a link J with a rod K which

runs above the deck at the side of the removable part F and at its rear end is threaded through a nut L operated by a hand wheel in the cock pit so that the operator can pull the rod and lift the removable 60 bow out of the path of the torpedo as shown in dotted lines. The bulkhead M between the cock pit and the forward part of the boat is extended upward above the deck and provided with a window N through 65 which the operator can look forward, and the rod K extends through this upward extension of the bulkhead.

Strapped or otherwise fixed on the underside of the hinged deck F is a torpedo tube 70 O of any usual or suitable type. The deck and tube are adapted to be swung up together to the position of Fig. 1 so that the end of the tube will be above the adjacent end of the deck P of the cock pit and at 75 such an angle that a torpedo Q can be introduced lengthwise into the tube as indicated in dotted lines. The tube will then be lowered and the torpedo will be in position for launching. When this is to be 80 done the operator first raises the bow section G out of the way and then by compressed air or by an explosion in the rear of the torpedo drives it out of the tube and out of the boat and starts its engine. Or 85 he may merely release the torpedo from the usual holding devices within the tube and start its engine, leaving it to propel itself out of the tube. A variety of devices is known for launching torpedoes and 90 as these form specifically no part of my invention they are not illustrated, nor are the controlling devices which of course will be in the operator's compartment or cock pit. 95

Any suitable mechanism may be used for raising the deck and rendering the tube accessible for loading. This may in fact be done by tackle overhead similar to that which is used for lowering and introducing 100 the torpedo. Preferably, however, mechanism for lifting the deck and tube will be provided within the boat, as an example I have shown a toggle mechanism comprising a link R connected at its upper end to a strap on the tube and at its lower to a block S which slides in suitable guides in the bottom of the boat and which is actuated by means of a rod T passing through 105 a stuffing box in the bulkhead M and into 110

the operator's compartment where it is connected to a rack U driven by a pinion V which in turn is driven from the boat's engine and which may be reversed or held stationary at the will of the operator. Pushing the rod T forward lowers the loaded tube and deck, and pulling it rearward lifts them to position for loading.

The hull of the boat is preferably provided with flotation chambers W (Fig. 3) for maintaining it at the desired level, their capacity being such that the boat will run with its deck practically awash when loaded with a torpedo, and will sink a little lower when the bow is opened and water admitted.

In the construction shown in Figs. 4 and 5 the torpedo tube is not fastened to the removable deck. Instead, this deck F' is hinged along one of its sides and the tube is mounted in the boat comprising a lower section Q' equal to or slightly less than half the circumference and sections Q^2 hinged along the sides to the section Q' so that they may be spread in the manner shown in Fig. 4 to permit the torpedo to be lowered in a horizontal position into place, after which the sections Q^2 will be folded together on the torpedo and constitute a complete tube. In other respects the boat will be constructed and operated as shown in connection with Fig. 1.

Though I have described with great particularity of detail certain embodiments of

my invention yet it is not to be understood therefrom that the invention is restricted to the particular embodiments illustrated. Various modifications may be made in detail and in the arrangement of the parts without departing from the invention as defined in the following claims.

What I claim is—

1. A torpedo boat having a closed space for carrying its operating mechanism and a torpedo receiving space, a torpedo tube carried in said torpedo-receiving space and a movable deck for said torpedo-receiving space, said tube being directly accessible by the opening of said deck.

2. A torpedo boat having at the rear a closed space for carrying its operating mechanism, the remaining forward space being just sufficient in length to accommodate a torpedo and a torpedo tube carried in said forward space.

3. A torpedo boat having at the rear a closed space for carrying its operating mechanism, the remaining forward space being just sufficient in length to accommodate a torpedo and a torpedo tube carried in said forward space, and a movable deck for said forward space, said tube being directly accessible by the opening of said deck.

In witness whereof, I have hereunto signed my name.

WILLIAM B. SHEARER.
